UNITED STATES PATENT OFFICE.

VOLNEY A. SEARLES, OF JACKSON, MICHIGAN, ASSIGNOR TO STEWART-WARNER SPEEDOMETER CORPORATION, OF CHICAGO, ILLINOIS, A CORPORATION OF VIRGINIA.

LIQUID-FEEDING DEVICE.

Application filed October 19, 1923. Serial No. 669,477.

This invention relates to certain improvements in liquid feeding devices for use particularly in supplying liquid fuel to internal combustion engines of automobiles and the like in connection with which it is very often desirable to have the primary fuel tank carried on the vehicle at a level below the carburetor.

Such tank structures usually embody an upper chamber and a lower chamber, with valved means of communication between them for effecting direct discharges from the upper to the lower chamber when atmospheric pressure is produced in the upper chamber.

The primary object of this invention is to provide a new and novel means of affording communication between the upper and the lower chamber for effecting the desired discharge of liquid fuel from said upper chamber to the lower chamber.

Other objects and advantages relate to the details of construction and operation of the device, as will more fully appear from the following description taken in connection with the accompanying drawings, in which:

Figure 1 is a vertical sectional view of an embodiment of my invention.

Figure 2 is a section (somewhat enlarged) of the valve casing controlling the siphon device.

Figure 3 is a vertical sectional view of a slightly different embodiment of my invention.

As illustrated in Figure 1, the tank —1— comprises an upper chamber —2— and a lower chamber —3—, the upper chamber adapted to be alternately under vacuum and at atmospheric pressure, while the lower chamber is maintained at all times at atmospheric pressure for affording free gravity discharge of fuel to the carburetor.

The upper chamber —2— is provided with a liquid inlet connection —4— which may be in communication with any suitable source of supply, as the ordinary tank carried by an automobile. A suction connection —5— is provided which may be in communication with the manifold of the engine.

An air vent, or atmospheric inlet —6—, is provided, controlled by an upwardly opening valve —7— actuated in a manner hereinafter described.

The suction connection —5— is controlled by a downwardly opening valve —8—

mounted upon a float stem —9— and adapted to move in connection with the stem to open and closed position in accordance with the level of liquid in the chamber —2—.

These valves and their connections and operating mechanism are of the same construction as illustrated in Letters Patent No. 1,255,347 issued to William Sparks under date of February 5, 1918.

As shown, the valve —7— is mounted upon a lever —10— having its inner end pivoted on lugs —11— formed in connection with plate —12— secured to the cap —13— of the tank structure. This lever —10— is adapted to be snapped to opposite sides of its pivot by means of a pair of springs —14— having their inner ends connected to the float, the outer end of one of the springs being connected to the lever —10— while the outer end of the other spring is connected to projection —15— extending downwardly from plate —12—. The operation of this structure is well known. The lower end of the float stem —9— may be provided with a guide —15'— mounted upon partition wall —16— which separates the tank —1— into the chambers —2— and —3—.

Pipe —17— constitutes a means for maintaining at all times atmospheric pressure in the chamber —3—, and may as shown, communicate with the nipple —18— surrounding the air vent or atmospheric inlet.

The means of communication between chambers —2— and —3— is effected by a siphonic arrangement, which consists of the siphon tube —19— having its lower end projecting through partition —16— and extending downwardly some distance into the chamber —3—, while its other leg —20— penetrates a valve casing —21— and is provided with lateral openings —22— in communication with the interior of the casing. This valve casing —21— is provided with an interior valve seat —23— upon which the valve —24— is adapted to be seated so as to be held closed and by suction or vacuum produced in chamber —2—. The valve —24— is of disk-shape form and is loosely carried by a float —24'— mounted in the valve casing, and movable therein into contact with the lower end of the leg —20— of the siphon tube —19—. The relative formation of these parts is of such a character that the float —24'— when buoyed by liquid in the casing —21— has sufficient elevating force to

raise the valve --23-- from its seat. In other words, the buoyancy of the float is slightly greater than the weight of the disk valve.

5 The operation will be readily understood. When vacuum is produced in chamber --2-- the valve --24-- is drawn to its seat and is maintained in that position so long as the minus pressure exists in chamber --2--. As 10 soon, however, as the float is raised to that position where it closes the suction connection --5-- and opens the air vent --6--, then the disk valve --23-- is opened by weight of the liquid and the buoyancy of float 15 --24-- maintains this valve --24-- in its open position, while the liquid siphons through the tube --19-- into the lower chamber --3--.

In Figure 3 a slightly different arrangement is shown in that the siphon tube --19-- embodies a substantially vertically extending cylindrical portion --25-- positioned within chamber --2-- formed at its bottom with a valve seat --26-- for engagement with the 25 valve --27-- carried by float --28-- positioned within the cylindrical part --25--, the valve being limited in its upward movement by means of one or more projections --29-- extending within the cylinder --25--. 30 In this case in like manner, the buoyancy of float --28-- is slightly greater than the weight of the valve --27--.

In this construction, the siphon tube extends outside the tank structure and communicates at its lower end with a nipple --29'-- exterior of the tank structure, but in communication therewith through conduit --30-- so that the liquid fuel in this case siphons from the upper chamber --2-- through the nipple --25-- into the lower chamber --3-- from whence it may be discharged by gravity through a nipple --31-- to a carburetor, or other device.

For the purpose of priming the device when 45 drained, or when the siphon feed stops, a pipe --32-- is provided which is connected to any suitable source of vacuum, as the vacuum line which is connected to the upper chamber, or the pipe --32-- may communicate directly with the manifold of the engine. The communication of the pipe --32-- with the interior of the nipple --29'-- is controlled by means of a valve --33-- which 50 can be opened or closed at will.

55 The operation of this structure will be readily understood, in that when atmospheric pressure is produced in the upper chamber, the valve --27-- opens and the liquid siphons into the lower chamber --3--. When suction is produced in the upper chamber, the valve --27-- closes and remains in closed position while sufficient liquid is elevated in the chamber so as to raise the float to a position where it closes the suction valve --8--.

60 65 Although I have shown and described a

specific construction illustrative of embodiments of my invention, I do not desire to limit myself to the details of construction of the same, as various changes and modifications may be made without departing from the invention as set forth in the appended claims.

I claim:

1. In a device of the class described, an upper chamber having a liquid inlet, an air exhaust connection and an air inlet, means for alternating atmospheric pressure and vacuum in said upper chamber; a siphon tube leading from the upper chamber to the lower chamber and a valve controlling the opening of the siphon tube in the upper chamber, adapted to be held seated by the vacuum in said chamber.

2. In the combination defined in claim 1, said siphon tube opening downwardly in the upper chamber, the valve therefor being arranged to seat downwardly to close said opening, and a float attached to said valve for unseating it when the vacuum in the upper chamber is relieved.

3. In a device of the class described, a tank structure comprising an upper chamber and a lower chamber, an atmospheric connection, an air exhaust connection and a liquid inlet to said upper chamber, means for maintaining atmospheric pressure in the lower chamber, means for alternating vacuum and atmospheric pressure in the upper chamber, a siphon tube having one leg in communication with the upper chamber and its opposite leg in communication with the lower chamber, a valve within the siphon tube, and a float connected to the valve and of sufficient buoyancy to move the valve from its seat under atmospheric pressure conditions in the upper chamber.

4. In a device of the class described, a tank structure comprising an upper chamber and a lower chamber, means for alternating vacuum and atmospheric pressure in the upper chamber, a siphon tube having one leg in communication with the upper chamber and its opposite leg in communication with the lower chamber, a valve arranged within the siphon tube and having a limited movement therein, and a float connected to the valve of sufficient buoyancy to move the valve from its seat under atmospheric conditions in the upper chamber.

5. In the combination defined in claim 3, the end of the siphon tube in the upper chamber having an enlargement providing a valve chamber and the said float being accommodated and confined in said valve member.

In testimony whereof I have hereunto set my hand at Jackson, Michigan, this 2nd day of October, 1923.

VOLNEY A. SEARLES.
